(57) CLAIM

The ornamental design for a pants, as shown and described.

DESCRIPTION

FIG. 1 is a left front perspective view of pants showing my new design;

FIG. 2 is a right front perspective view thereof;

FIG. 3 is a front view thereof;

FIG. 4 is a rear view thereof;

FIG. 5 is a left side view thereof; and,

FIG. 6 is a right side view thereof.

The broken lines immediately adjacent to the shaded area represent unclaimed boundaries of the design. The contrast in shading represents a contrast in appearance only and does not represent any particular color, material, texture or finish. The broken lines showing the remainder of the pants are for environmental purposes only and form no part of the claimed design.
